(57) **CLAIM**

The ornamental design for a beach mesh bag as shown and described.

DESCRIPTION

FIG. 1 is a front, right, and top perspective view of a beach mesh bag, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a detailed view taken from the encircled portion labeled "9" in FIG. 1;

FIG. 10 is a detailed view taken from the encircled portion labeled "10" in FIG. 2;

FIG. 11 is a detailed view taken from the encircled portion labeled "11" in FIG. 7; and,

FIG. 12 is a detailed view taken from the encircled portion labeled "12" in FIG. 8.

The short-dash and long-dash broken lines in FIGS. 1, 2, and 7-12 denote the boundaries of the detail areas and form no part of the claimed design. The even spaced broken lines in the drawings depict portions of the beach mesh bag that form no part of the claimed design.

1 Claim, 12 Drawing Sheets
